SHUTTLE CHECK

Application filed January 15, 1929. Serial No. 332,705.

This invention relates to shuttle checks for looms and it is the general object of the invention to provide a simple check wherein the checking action is caused by the shuttle itself.

In weft replenishing looms it is important to have the shuttles properly placed with respect to the magazines and weft detectors so that these mechanisms can always cooperate properly with the bobbin. It is an important object of my present invention to provide a shuttle check which is movable with respect to a fixed pivot and divided into two arms, one the shuttle engaging arm and the other the binder or pressure exerting arm, these arms being variable as to length to effect a range of pressures which may be necessary when the speed of the loom is increased or decreased.

It is a further object of my present invention to provide a shuttle check having an arm to engage the rounded portion of the shuttle and to provide said check with a mounting so that said arm may be given a greater or lesser movement depending upon the amount of the rounded portion of the shuttle which it engages.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a top plan view of a lay end having my invention applied thereto,

Fig. 2 is a front elevation of a portion of a structure shown in Fig. 1 taken in the direction of arrow 2, of the latter figure, and

Fig. 3 is an enlarged vertical section on line 3—3 of Fig. 1.

Referring to Fig. 1 I have indicated the lay 10 having a box back 11 and a binder 12 supported by a stud 13 upstanding from the box plate 14. The shuttle S when properly boxed is located between the box back 11 and the binder 12. A picker 15 may be mounted on the upper end of a picker stick 16 to be given a shuttle propelling move-

ment every alternate pick of the loom when the lay of the loom is provided with a single box at one end. The structure thus far described is of the usual form.

In carrying my invention into effect I provide the box plate 14 with a forwardly extending horn 20 into which is threaded as at 21 the lower end of a stud 22. The latter extends through a carrier 23, upward motion of which is restrained by head 24 of the stud. The carrier is confined between the head and the horn 20 but is free to rotate about the stud.

The shuttle check includes in its construction a single strip of resilient metal such as tempered steel indicated generally at 30 having the right hand end thereof as viewed in Fig. 1 curved as at 31 and provided with a leather facing 32. The facing is designed to engage the rounded edge C of the shuttle S. The shuttle check is provided with a rear substantially straight limb 33 the left hand end of which as viewed in Fig. 1 is bent toward the binder to engage the latter at a rounded portion or nose 34. From the nose the strip of material is curved forwardly and to the right and extends in a second substantially straight limb 35 behind the pivot defined by the stud. Extending through the end 36 of the forward limb 35 is a screw 37 having nuts 39 one on either side of the limb. These nuts may hold the screw 37 adjustably against the rear limb 33 to reinforce the latter.

The carrier 23 is provided with a recess 40 which receives the limb 33 while the forward portion of said carrier is provided with a second recess 41 in which lies the forward limb.

As shown in Fig. 2 the forward portion of the check is provided with a slot 42 through which extends a pair of screws 43. These screws extend into the carrier and clamp the forward portion of the check tightly to the carrier. The rear limb 33 is free to move in the slot 40, not being clamped directly to the carrier but being held in close relation with the latter partly by the bolt 37.

The stud 22 is normally in fixed position with respect to the box plate and therefore

with respect to the shuttle when the latter is properly boxed. As the shuttle enters the box the curved portion C will engage the leather facing 32 and rock the check in a 5 clock-wise direction as viewed in Fig. 1 around the stud 22, thus pressing the rounded nose 34 against the binder 12. The effect of this action is to increase the pressure of the binder against the shuttle and thereby check movement of the latter in the 10 box to avoid rebounding.

If it is desired to vary the checking effect on the shuttle the screws 43 may be loosened and the check moved either to the right or 15 to the left, as desired, with respect to the carrier 23, the screws 43 being tightened when the check is in proper position. By varying the position of the nuts 39 with respect to the screw 37 it will be possible to 20 change the relation between the substantially parallel limbs 33 and 35 to effect a corresponding change between the shuttle and binder engaging arms. In this way I am able to secure a variety of adjustments and 25 also to vary the time of application of the maximum force exerted by the check when compared with the travel of the shuttle into the box toward the picker.

When the shuttle check is moved to the 30 left of the position shown in Fig. 1 the leather facing 32 will be engaged at an earlier time in the flight of the shuttle so that the nose 34 will be moved against the binder earlier in the pick. This movement 35 of the check will of course apply the pressure exerted by the nose 34 at a point more distant from the pivot of the binder so as to increase the leverage of the latter. If in the new position assumed the leverage 40 should be found correct but the time of action too late the screw 37 may be changed so as to move the leather faced end of the check rearwardly, this adjustment being permissible due to the fact that the material 45 of which the binder is formed is resilient and that the screw 37 acts to force the limb 33 away from limb 35.

From the foregoing it will be seen that I have provided a shuttle check formed essentially of a single strip of resilient material which is held to a carrier movable around an axis preferably fixed though not necessarily so with respect to the box. It will further be seen that the check may be 55 moved either to the right or to the left with regard to the carrier by manipulation of the screws 43. It will also be seen that the relation of the shuttle engaging arm with respect to the binder engaging nose may be 60 varied by means of the screw 37.

Having thus described my invention it will be seen that changes and modifications may be made therein by those skilled in the art without departing from the spirit and 65 scope of the invention and I do not wish

to be limited to the details herein disclosed, but what I claim is:

1. In a shuttle check for a loom having a lay with a binder to engage a shuttle, means defining a pivot, an inherently resilient shuttle check extending on opposite sides of the pivot and having one arm to engage the rounded end of the shuttle and the other arm to engage the binder, means to hold the shuttle check, said means having connection with the aforesaid pivot, and a device to vary the amount of the shuttle check which extends to one side of the pivot. 70

2. In a shuttle check for a loom having a lay with a binder to engage a shuttle with a rounded end, means defining a pivot, a shuttle check formed of inherently resilient material and having an arm on one side of the pivot to engage the shuttle and another arm on the other side of the pivot to engage the binder, a carrier for said check movable about and supported by the pivot and secured to the check, and means to vary the amount of the shuttle engaging arm which extends to one side of the pivot. 80

3. In a shuttle check for a loom having a lay with a binder to engage a shuttle, means defining a pivot, a shuttle check formed of inherently resilient material having a shuttle engaging arm extending to one side of the pivot and a binder engaging arm extending to the other side of the pivot, a carrier supported by and movable angularly by the aforesaid pivot, and means to hold the shuttle check to the carrier in any one of a plurality of positions to vary the length of a shuttle engaging arm which extends to one side of the pivot. 90

4. In a shuttle check for a loom having a lay with a binder to engage a shuttle, means defining a pivot, a shuttle check formed of inherently resilient material and having a shuttle engaging arm extending to one side of the pivot and a binder engaging arm extending to the other side of the pivot, a carrier supported by and angularly movable with respect to the pivot, said shuttle check having a slot therein, and a screw extending through the slot and into the carrier to hold said shuttle check in any one of a plurality of positions with respect to the pivot to vary the length of the shuttle engaging arm which extends to one side of the pivot. 100

5. In a shuttle check for a loom having a lay with a binder to engage a shuttle, means defining a pivot, a shuttle check formed of inherently resilient material and having a shuttle engaging arm on one side of the pivot, said resilient material being bent back on itself to provide two substantially parallel limbs defining a binder engaging arm, a carrier operatively related to both the limbs and secured to one of them, said car- 110

rier being supported by and movable angularly with respect to the pivot.

6. In a shuttle check for a loom having a lay with a binder to engage a shuttle, means defining a pivot, a shuttle check formed of inherently resilient material and having a shuttle engaging arm on one side of the pivot, said resilient material being bent back on itself to provide two substantially parallel limbs defining a binder engaging arm, a carrier operatively related to both the limbs and secured to one of them, said carrier being supported by and movable angularly with respect to the pivot, said carrier being connected to one limb only of the binder engaging arm.

7. In a shuttle check for a loom having a lay with a binder to engage a shuttle, means defining a pivot, a shuttle check formed of inherently resilient material and having a shuttle engaging arm on one side of the pivot and a binder engaging arm bent back on itself to provide two substantially parallel limbs on the other side of the pivot, a carrier supported by and angularly movable with respect to the pivot, said shuttle check having a slot therein, and a screw extending through the slot and into the carrier to hold said shuttle check in any one of a plurality of positions with respect to the pivot to vary the length of the binder engaging arm which extends to one side of the pivot, said carrier being secured to the forward limb of the binder engaging arm and having guiding relation with respect to the rear limb.

8. In a shuttle check for a loom having a lay with a binder to engage a shuttle, means defining a pivot, a shuttle check formed of a length of resilient material bent on itself, said material having a shuttle engaging arm located to one side of the pivot and said material having a portion thereof bent back on itself to define two substantially parallel limbs which define a resilient binder engaging arm on the other side of the pivot, a carrier located between the limbs and supported by and movable angularly with respect to the pivot, and means to hold one of the limbs to the carrier.

9. In a shuttle check for a loom having a lay with a binder to engage a shuttle, means defining a pivot, a shuttle check formed of a length of resilient material bent on itself, said material having a shuttle engaging arm located to one side of the pivot and said material having a portion thereof bent back on itself to define two substantially parallel limbs which define a resilient binder engaging arm on the other side of the pivot, a carrier located between the limbs and supported by and movable angularly with respect to the pivot, means to hold one of the limbs to the carrier, and means interposed between the limbs to draw the latter together at a point removed from the pivot.

10. In a shuttle check for a loom having a lay with a binder to engage a shuttle, means defining a pivot, a shuttle check having a pair of substantially parallel arms which are formed of resilient material and extend on both sides of the pivot, said limbs being connected together on one side of the pivot to define a binder engaging arm, a carrier for the limbs pivotally supported by the aforesaid pivot, and a shuttle engaging arm formed as an extension from one of the limbs.

11. In a shuttle check for a loom having a lay with a binder to engage a shuttle, means defining a pivot, a shuttle check having a pair of substantially parallel arms which are formed of resilient material and extend on both sides of the pivot, said limbs being connected together on one side of the pivot to define a binder engaging arm, a carrier for the limbs pivotally supported by the aforesaid pivot, a shuttle engaging arm formed as an extension from one of the limbs, and means connecting the limbs on that side of the pivot adjacent the shuttle engaging arm to vary the distance between said limbs.

12. In a shuttle check for a loom having a lay with a binder to engage a shuttle, means defining a pivot, a shuttle check formed of a strip of inherently resilient material, said check having a shuttle engaging arm on one side of the pivot and having two substantially parallel limbs which extend on both sides of the pivot, the arms being connected together on the side of the pivot opposite the shuttle engaging arm to define a binder engaging arm, and screw means located between the limbs on that side of the pivot opposite the binder engaging arm to vary the distance between said limbs.

13. In a shuttle check for a loom having a lay with a binder to engage a shuttle, means defining a pivot, a shuttle check formed of a strip of inherently resilient material, a carrier movable angularly about the pivot and having substantially horizontal slots on opposite sides thereof to receive the shuttle check, the latter having a shuttle engaging arm located on one side of the pivot and a binder engaging arm on the other side of the pivot, and means to hold said check in fixed relation with respect to the carrier.

14. In a shuttle check for a loom having a lay with a binder to engage a shuttle, means defining a pivot, a shuttle check formed of a strip of inherently resilient material having a shuttle engaging arm on one side of the pivot, a pair of substantially parallel limbs extending on both sides of the pivot, those portions of the limbs extending on that side of the pivot opposite the shuttle engaging arm being connected together to form a binder engaging arm, a carrier an-
